SCAFFOLDING SUPPORT

King A. Steen, Springfield, Mo.

Application March 30, 1956, Serial No. 575,221

1 Claim. (Cl. 304—6)

2

This invention relates to improvements in scaffolding supports or trestles.

An important object of the invention is to provide a scaffolding support having legs which are individually adjustable in length, so that the scaffolding may be erected upon unlevel or rough terrain.

A further object is to provide novel and simplified means for effecting the quick adjustment of the individual legs of the trestle, and enabling the legs to be releasably locked in selected adjusted positions in a safe and convenient manner.

Another object is to provide means for quickly and conveniently adjusting the lengths of the legs, without necessitating the removal of fastener elements, or the complete separation of any parts of the device.

A still further object is to provide in a trestle of the above mentioned character novel and extremely strong and reliable means to facilitate the erection of extended or taller scaffolding upon the trestle of the instant invention.

Another object is to provide a novel and simplified adapter upon the trestle to facilitate erecting or building additional scaffolding thereon.

Other objects and advantages of the invention will be apparent during the course of the following description.

In the accompanying drawings, forming a part of this application, and in which like numerals are employed to designate like parts throughout the same,

Figure 1 is a perspective view of a scaffolding support or trestle in accordance with the invention,

Figure 2 is an enlarged end elevation of the same with parts broken away,

Figure 3 is an enlarged fragmentary elevational view of one telescoping leg and associated adjusting means,

Figure 4 is a longitudinal vertical section taken on line 4—4 of Figure 3,

Figure 5 is a horizontal transverse section taken on line 5—5 of Figure 3.

In the drawings, where for the purpose of illustration is shown a preferred embodiment of the invention:

The numeral 10 designates generally leg or support units of the trestle. Each unit 10 embodies a pair of upwardly converging inclined legs, each of said legs comprising upper and lower telescoping leg sections 11 and 12, as indicated. The upper leg sections 11 are tubular and straight, throughout major portions of their lengths, for the reception of the lower leg sections 12, which are also preferably tubular for the sake of lightness.

The upper leg sections 11 are preferably rigidly connected near and above their lower ends by transverse horizontal tubular braces 13, rigidly secured thereto by welding or the like. Similar shorter horizontal braces 14 preferably rigidly connect the leg sections 11 near their upper ends, as shown. Above the braces 14, the leg sections 11 have relatively short upstanding vertical extensions 15, integral therewith, and being tubular and having their upper ends open, as shown.

The leg units 10 are connected in assembly by an

elongated horizontal plank 16, or the like, having end portions resting upon the braces 14 between the vertical leg extensions 15, in close relation thereto, as shown. Vertically spaced transverse bolts 17 engage through registering openings provided in the plank 16 and extensions 15 for rigidly securing the plank to the units 10. Suitable diagonal braces 18 are preferably provided, having their upper ends secured as at 19 to the plank, and their lower ends rigidly secured as at 20 to the horizontal braces 13, at the longitudinal centers of the latter. The arrangement above described renders the support or trestle extremely rigid and sturdy in construction, yet lightweight, due to the use of metal tubing in the leg units 10.

Means are provided to effect the longitudinal adjustment of each individual leg of the trestle. Such means comprises a longitudinal slot 21 in each upper tubular leg section 11, extending throughout a major portion of the length thereof, and preferably extending approximately for the full distance between the braces 13 and 14, as shown. The upper and lower ends of the slots 21 are closed. Each longitudinal slot 21 includes a plurality of longitudinally equidistantly spaced branch slots or notches 22, opening through the inner longitudinal edge of the slot 21. The branch slots 22 of each tubular leg section 11 are parallel and upwardly inclined from the horizontal, for a purpose to be described. Any desired number of the branch slots 22 may be formed through each leg section 11, depending upon the degree of fineness of adjustability which it is desired to impart to each leg of the trestle. As shown in the drawings, the slots or notches 22 of the upper leg sections 11 of each unit 10 converge upwardly, Figure 2, and extend from the longitudinal slots 21, toward the inner sides of the two upwardly converging legs of the unit 10.

The lower tubular leg sections 12, which are of course smaller in diameter than the upper leg sections 11 into which they fit telescopically, are each provided near and below their upper ends with a transverse screw-threaded stud or pin element 23, rigidly secured thereto, preferably in the manner shown in Figure 4, or by welding, brazing, or by other suitable means. The screw-threaded element 23 of each lower leg section 12 engages slidably through the slot 21 of the adjacent tubular leg section 11, and the element 23 is preferably arranged at right angles to the tubular leg sections 11 and 12, as best shown in Figure 4. The element 23 projects somewhat beyond the outer surface of the upper leg section 11 and receives upon its outer end a winged nut 24, or the like. Each element 23 is freely shiftable longitudinally of its associated slot 21, and freely engageable and disengageable with any and all of the upwardly inclined branch slots 22. It is to be noted here that each branch slot 22 or notch forms with the inner longitudinal edge of the adjacent longitudinal slot 21 a downwardly directed tapered or V-shaped safety locking shoulder 25 for the pin element 23, as will be further described.

In order to effect the lengthening or shortening of each leg of the trestle, it is merely necessary to loosen the nut 24 slightly and to turn the lower leg section 12 somewhat upon its longitudinal axis for moving the element 23 out of the particular notch 22 within which it was previously located. The element 23 is now arranged in the longitudinal slot 21, and may be readily shifted lengthwise therein as the leg section 12 is adjusted lengthwise for the desired extent. The leg section 12 is then twisted or turned slightly in the opposite direction to cause the element 23 to enter and engage within a different one of the notches 22. At this time, the nut 24 is re-tightened for clamping or locking the leg sections

11 and 12 in the selected longitudinally adjusted condition.

In connection with the above, it is to be noted that the inclination of the notches 22 and the resulting formation of the shoulders 25 causes the elements 23 to lock ever more securely within the notches 22 when the weight upon the trestle increases. In other words, the greater the weight to be supported, the more securely the element 23 secures the leg sections 11 and 12 in their selected adjusted position, due to the novel coaction of the element 23 with the inclined notches or branch slots 22. The arrangement is highly simplified, extremely compact, strong and foolproof in operation. It is substantially impossible for one of the trestle legs to slip under load, once the proper adjustment has been made, as above described, and the nut 24 tightened.

Novel means are provided to facilitate erecting extended scaffolding upon the trestle as shown in Figure 1. This means comprises an adapter 26 for the top of each leg unit 10, as shown. Each adapter 26 comprises a horizontal plate section 27, carrying a pair of depending vertical tubular legs or bars 28, rigidly secured thereto by welding or the like in parallel spaced relation. The legs 28 are spaced to enter the tops of the tubular extensions 15, as shown in the drawings, and the legs 28 are preferably somewhat longer than the vertical extensions 15, Figure 2, so as to project above the latter in assembly, when they are inserted into the extensions 15 to the fullest extent, Figure 2. The legs 28 are formed with transverse openings to receive the same bolts 17 which secure the units 10 to the plank 16, and the bolts 17 therefore pass through extensions 15, legs 28 and the plank 16, as shown. The adapters 26 are thus safely and rigidly secured to the trestle.

Each adapter 26 further comprises a short central vertical upstanding sleeve or tube section 29, rigidly secured to the top of the plate 27, by welding or the like, the top of each sleeve 29 being open. The short sleeves 29 are adapted to receive within them and to anchor the vertical legs 30 of conventional tubular metal scaffolding 31, in the manner shown in Figure 1. The scaffolding 31 is thus firmly and safely mounted upon the trestle, through the medium of the simplified adapters 26, and the arrangement is extremely strong, safe and reliable.

While the invention has been described above in connection with a single support or trestle, as shown in Figure 1, it will be understood by those skilled in the art that the trestle is adapted to be used in pairs for supporting scaffolding, and further description in this regard is believed to be unnecessary.

It is to be understood that the form of the invention, herewith shown and described is to be taken as a preferred example of the same, and that various changes in the shape, size and arrangement of parts may be resorted to, without departing from the spirit of the invention or the scope of the subjoined claim.

Having thus described my invention, I claim:

A scaffolding support comprising a pair of leg units, each leg unit including a pair of spaced substantially vertical tubular extensions having their tops open, a plank for connecting the leg units having end portions engaging between the pairs of extensions, bolt means engageable through said extensions and end portions for securing the plank to the leg units, scaffolding adapters for the tops of the leg units, each adapter comprising a substantially horizontal body portion, a pair of depending vertical legs secured to the body portion and engageable within the tops of the tubular extensions and having transverse openings to receive said bolt means, and upstanding sleeves secured to the tops of said body portions for receiving vertical legs of scaffolding.
